ELECTRIC CAN OPENER

Raymond W. Newsom and Sherman A. Newsom,
Alpine, Tex.

Application October 14, 1953, Serial No. 385,936

8 Claims. (Cl. 30—4)

1

This invention relates in general to improvements in can openers, and more specifically to an electric can opener.

The primary object of this invention is to provide an improved can opener which is automatic in operation and which is operated in response to the positioning of a can relative to the can opening mechanism.

Another object of this invention is to provide an improved can opener of the punch type, the can opener including a driven punch which is automatically actuated in response to the positioning of a can beneath such punch.

A further object of this invention is to provide an improved can opener which includes a punch-type can opening device, the can opening device being driven by drive means which are automatically actuated and which are so designed whereby they are one complete cycle.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the can opening device which is the subject of this invention and shows the same ready for the reception of a can to be opened;

Figure 2 is a longitudinal transverse sectional view taken substantially upon the plane indicated by the section line 2—2 of Figure 1 and shows the general cross-section of the interior of the can opening device;

Figure 3 is a longitudinal vertical sectional view taken through the can opener of Figure 1 and shows the same near the end of a can opening cycle, selected positions of the can opener being shown in dotted lines;

Figure 4 is a transverse horizontal sectional view taken substantially upon the plane indicated by the section line 4—4 of Figure 1 and shows the mechanism of the can opener as viewed from the top; and

Figure 5 is a wiring diagram of the electrical control means for the can opener.

Referring now to the drawings in detail, it will be seen that the electric can opener which is the subject of this invention includes an elongated base 10. Extending upwardly from the base 10 at the rear end thereof is a U-shaped mounting bracket which includes a lower horizontal web 12 and upstanding flanges 14 and 16.

Carried by the base, which is L-shaped in plan

2

view, as is best illustrated in Figure 4, adjacent the forward end thereof is an L-shaped support which includes a transversely extending leg 18 and a longitudinally extending leg 20, the longitudinally extending leg 20 being disposed adjacent the center of the base 10.

Removably secured to the transverse leg 18 and extending upwardly from the base 10 is a front portion 22 of an enlarged housing which is referred to in general by the reference numeral 24. The housing 24 also includes an L-shaped rear portion 26 which is suitably secured to both the front portion 22 and the U-shaped support by fasteners 28 and 30, respectively.

As is best illustrated in Figures 2 and 4, the U-shaped support is disposed at one side of the rear portion of the base 10 and is aligned with the L-shaped support. Disposed in offset relation to the two supports is a motor mounting block 32 which is carried by the base 10. Suitably secured to the motor mounting block 32 by fasteners 34 is an electric motor 36 which includes an armature shaft 38. Secured to the armature shaft 38 by a coupling 40 is a shaft 42. The shaft 42 is journaled in the flange 14 and has removably secured thereto a first gear 44. The gear 44 is in the form of a pinion gear and is spaced from the flange 14 towards the flange 16. The gear 44 is engaged with a relatively large gear 46 which is rotatably journaled on a shaft 48 carried by the flange 14.

Connected to the gear 46 for rotation therewith is a pinion gear 50. The pinion gear 50 is disposed towards the flange 16 and is intermeshed with a relatively large gear 52. The gear 52 is rotatably journaled on a shaft 54 carried by the flange 14 and is spaced therefrom by a spacer 56. Secured to the gear 52 for rotation therewith is a cam wheel 58 which has carried thereby in eccentrically disposed relation a cam roller 60, the cam roller 60 being rotatably mounted on a pin 62 carried by the cam wheel 58.

As is best illustrated in Figure 3, the front portion 22 of the housing 24 is provided with a rectangular opening in the upper part of the front wall thereof, the opening being referred to by the reference numeral 64 and being aligned with a similar rectangular opening 66 in the transverse leg 18. Extending transversely of the opening 66 and carried by the transverse leg 18 is a pivot pin 68. Pivotally mounted on the pivot pin 68 is an elongated lever 70 which has carried at its forward end a punch which forms a can opener 72.

It will be noted that the lever 70 is of a length so as to overlie the cam roller 60 in all positions thereof. In order that the lever 70 may be re-

tained in engagement with the cam roller 60 at all times, there is connected to the lever 70 intermediate its ends a spring 74 whose opposite end is connected to an intermediate part of the longitudinal leg 20. The spring 74 urges the rear portion of the lever 70 downwardly about the pivot pin 68.

As is best illustrated in Figures 1 and 4 the base 10 extends forwardly of the housing 24. Overlying the base 10 adjacent its forward edge is a can positioning block 76. The can positioning block 76 is provided with an arcuate recess 78 in which is adapted to be received the bottom of a can. In order to further facilitate the positioning of a can, such as the can 80 illustrated in Figure 3, the front wall of the front portion 22 of the housing is provided with a block 82 to prevent rearward tipping of the can 80 when engaged by the can opener 72.

In operation, when the electric motor 36 is energized the various gears are rotated to cause rotation of the cam wheel 58. Rotation of the cam wheel 58 causes the cam roller 60 to move from the solid line position of Figure 3 to the dotted line position. This causes the pivoting of the lever 70 from the solid line position to the dotted line position with the result that the can opener 72 is urged downwardly into the top wall of the can 80 and punches an opening therein as desired.

In order that operation of the electric motor 36 may be controlled, there is carried by the longitudinal leg 20 intermediate its upper and lower ends a switch 84. The switch 84 is provided with a control lever 86 which is normally retained in a circuit opening position by a coil spring 88 secured to the transverse leg 18.

In order to facilitate automatic operation of the switch 84, there is provided an actuator which is referred to in general by the reference numeral 90. The actuator 90 includes a horizontal arm 92 which extends through aligned openings 94 and 96 in the front wall of the forward portion 22 and the transverse leg 18, respectively. The horizontal leg 92 is provided at its forward end with a roller 98 which is engaged by a can 80 properly positioned on the base 10 and moved rearwardly. The horizontal leg 92 is provided at its upper surface with a notch 100 in which the lower end of the control lever 86 of the switch 84 is normally positioned, as is illustrated by the dotted line position of the actuator 90 in Figure 3.

The actuator 90 also includes a vertical arm 102 which is formed integrally with the rear end of the horizontal arm 92. The upper end of the vertical arm 102 is rounded as at 104 and there is connected to the vertical arm 102 adjacent its upper end one end of a spring 106. The opposite end of the spring 106 is connected to a rear edge of the longitudinal leg 20. It will be seen that the spring 106 urges the actuator 90 forwardly to the dotted line position illustrated in Figure 3.

When a can 80 is properly positioned on the base 10, the positioning thereof results in the rearward movement of the actuator 90 from the dotted line position illustrated in Figure 3. This results in the control lever 86 of the switch 84 being moved from its dotted line position and the completion of an electrical circuit to the electric motor 36. The drive mechanism of the can opener then operates in the above mentioned manner with the result that the cam roller 60 is moved relative to the shaft 54 about which it rotates in a clockwise direction as viewed in Fig. 3 and engages the rounded upper end 104 of the vertical arm 102.

This moves the actuator 90 downwardly to the solid line position of Figure 3 and releases the control lever 86. The spring 88 then returns the control lever 86 to its initial position and electric current to the electric motor 36 is cut off with the result that the various gears have a tendency to stop rotating.

In order to insure the stopping of the various gears at the end of a complete cycle, there is provided a brake assembly which is referred to in general by the reference numeral 110. The brake assembly 110 includes a brake drum 112 carried by the shaft 42 adjacent the flange 14. Selectively engaging the brake drum 112 is a brake arm 114 which has one end thereof pivotally connected to a mounting bracket 116 carried by the web 12. The other end of the brake arm 114 is pivotally connected to a plunger 118 of an electro-magnetic device 120. The electromagnetic device 120 is secured in place by a mounting bracket 122 carried by the web 112 adjacent its rear edge.

Actuation of the electromagnetic device 120 is controlled by a switch which is referred to in general by the reference numeral 124. The switch 124 includes a pair of spring arms 126 and 128 which have carried thereby opposed contacts 130 and 132. The contacts 130 and 132 are normally spaced apart so as to not permit actuation of the electromagnetic device 120. However, when the actuator 90 is moved downwardly by the cam roller 60 to the solid line position of Figure 3, a projecting element 134 carried by the underside of the horizontal arm 92 engages the spring strip 126 which causes the closing of contacts 130 and 132 to energize the electromagnetic device 120 thereby causing the actuation of the brake arm 114 and stopping of the rotation of the various gears. The electromagnetic device 120 is de-energized by the continued movement of the cam roller 60 past the actuator 90 which then moves upwardly due to the urging of the spring 106 thereby opening the contacts 130 and 132. The actuator 90 is returned to its initial position upon removal of the can 80.

It will be understood that the switch 84 and the switch 124 are connected into an electrical circuit which includes a pair of lead-in wires 140 and 142. The lead-in wires 140 and 142 may be connected to any convenient electrical source through the use of conventional electrical connections.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. An automatic can opener comprising a can support, a can opening device carried by said support, drive means for said can opening device including a motor, a can operated switch for said motor, brake means for automatically stopping said drive means at the end of a can opening cycle.
2. An automatic can opener comprising a can support, a can opening device carried by said support, drive means for said can opening device including a motor, a can operated switch for said motor, brake means for automatically stopping said drive means at the end of a can opening

cycle, said can opening device being of the can punching type and being carried by a pivoted lever.

3. An automatic can opener comprising a can support, a can opening device carried by said support, drive means for said can opening device including a motor, a can operated switch for said motor, brake means for automatically stopping said drive means at the end of a can opening cycle, said brake means being actuated by said drive means.

4. An automatic can opener comprising a can support, a can opening device carried by said support, drive means for said can opening device including a motor, a can operated switch for said motor, brake means for automatically stopping said drive means at the end of a can opening cycle, said brake means being actuated by said drive means, an actuating arm for said switch, said brake means being actuated by said actuating arm.

5. An automatic can opener comprising a can support, a can opening device carried by said support, drive means for said can opening device including a motor, a can operated switch for said motor, brake means for automatically stopping said drive means at the end of a can opening cycle, said can opening device including a pivoted lever, said drive means including a cam engaging said lever to actuate said can opening device.

6. An automatic can opener comprising a can support, a can opening device carried by said

support, drive means for said can opening device including a motor, a can operated switch for said motor, brake means for automatically stopping said drive means at the end of a can opening cycle, said can opening device including a pivoted lever, said drive means including a cam engaging said lever to actuate said can opening device, said brake means being actuated by said cam.

10 7. An automatic can opener comprising a can support, a can opening device carried by said support, drive means for said can opening device including a motor, a can operated switch for said motor, brake means for automatically stopping said drive means at the end of a can opening cycle, said can opening device including a pivoted lever, said drive means including a cam engaging said lever to actuate said can opening device, an actuating arm for said switch, said brake means being actuated by said cam.

15 8. An automatic can opener comprising a can support, a can opening device carried by said support, drive means for said can opening device including a motor, a can operated switch for said motor, brake means for automatically stopping said drive means at the end of a can opening cycle, said brake means including an electromagnetically actuated plunger, a second switch controlling said plunger, an actuating arm for controlling operation of said can actuated switch and said second switch.
